CYLINDER MOUNT

Francis S. Flick, Oak Park, and Walter J. Kudlaty, Elmhurst, Ill., assignors to Flick-Reedy Corporation, a corporation of Illinois

Application December 16, 1954, Serial No. 475,614

4 Claims. (Cl. 309—2)

This invention relates to a mounting for a piston and cylinder device and more particularly to a side or foot mounting of such character.

Piston and cylinder devices may be mounted in various manner dependent upon the space available and the type of action which the cylinder is to accomplish. Some mountings are pivotal while other fix the piston and cylinder device in position relative to a base. The present invention is concerned with the type of mountings referred to as "side" or "foot" mountings which hold the cylinder immovable relative to a base.

It is important that the mounting be rigid and permit keying of the cylinder against any movement. A desirable mounting should assume very little space and also be of such form that the distance between the mounting base and centerline of the cylinder is at a minimum. Bending of the cylinder head under load in the direction of any of its dimensions should be avoided. The location and form of the mounting may have a definite relation to and may minimize such bending or deflection under load. The mounting lugs should also be as close to each other as possible to minimize beam action between lugs on the cylinder head and mounting. At the same time, the mounting should be of such a character that it may be attached to the cylinder without disturbing the cylinder assembly or be readily interchangeable with other and different mountings. The present invention provides a new mounting which meets these desired features set out above.

It is, therefore, the principal object of this invention to provide a new and improved mount for a piston and cylinder device.

A further object is to provide a side or foot type mounting which may be secured as close as possible to the centerline of the cylinder.

Another object is to provide a side or foot mounting which substantially minimizes deflection in the cylinder under load.

Another object is to provide a detachable foot mounting for a cylinder that may lay within the longitudinal projection of the cylinder head or cap so as to retain both the minimum width and centerline heights of the cylinder without such mounting.

A further object is to provide a mounting which can be attached to the cylinder without substantially disturbing the cylinder assembly.

Other features, advantages and objects of the invention will be apparent from the following description taken in conjunction with the accompanying drawings in which:

Figure 1 is a side elevational view of a piston and cylinder device partially broken away to illustrate the cylinder mount of the present invention; and

Figure 2 is a sectional view taken substantially along line 2—2 in Figure 1, with the base and fastener omitted and looking toward the lefthand end of the cylinder as indicated.

The piston and cylinder device to which the present

2

mounting is to be applied is either air or hydraulic, both of which are manufactured to very close machine tolerances. The cylinders are intended for continuous service for very long periods of time without attention. The use of the cylinder is quite prevalent in the machine tool field in applications requiring very accurate strokes, pressures and operation throughout long life.

The cylinder illustrated in the figures of the drawing includes a brass or steel cylinder tube 3 mounted between a steel cap 4 and a similar head 5 closing the ends of the tube. A retainer plate 6 is placed adjacent the head and the whole assembly is held together by tie rods 7 extending through the cap, head and retainer plate with appropriate nuts 8 and 9 on either end of the tie rods. Suitable seals are provided between the tube 3 and the head and cap. An adjustable cushion 10 which may be in the form of a needle valve is shown at each end of the cylinder along with a ball check 11 for obtaining quick release and return of the piston within the cylinder. A piston rod 12 is shown as extending through the head 5 and is provided with a threaded outer end 13 and wrench flats 14. The piston within the cylinder is not shown as it forms no part of the present invention. Fluid may be led into either end of the cylinder through ports connected to piping 15 and 16. The device shown is thus a double acting piston although the invention is equally applicable to single acting piston and cylinder devices.

The mounting member of the present invention comprises a one-piece lug which takes the place of the ordinary nuts 8 used on the end of the tie rod 7. The lugs for any particular size of cylinder are interchangeable. Ordinarily four mounting lugs are used to secure a cylinder in place against a base support. Thus, the lugs would be attached to either end of the pair of tie rods on the side or end of the cylinder.

The particular lugs, generally indicated 17, are generally square in cross section as shown in Figure 2 and include a nut portion 18 having a threaded bore 19 for tightening the nut portion upon the threaded end 20 of the tie rod. The bore 19 is centrally located in the nut portion of the lug so that the lug may be placed on any particular tie rod interchangeably. The rearward portion 21 of the lug is provided with a cross bore 22 having an axis which intersects the axis of the threaded bore 19 at a right angle. The face 23 of the nut portion is smooth and flat so that it may abut against the machined surface of the cap or retainer plate as the case may be. The upper surface 24 and lower surface 25 are parallel and normal to the face 23 and the cross bore is normal to these surfaces. These relationships are retained even though the nut portion 18 of the lug might be turned down to clear the bushing 28 on an oversized piston rod.

The heads of the cylinder are accurately milled to seat on a base 29. The present mount permits the milled surface to be held tightly against the base. The retainer plate 6 is usually about .010" less in width than the head 5. The lug is given a dimension such that it may be about $\frac{1}{64}$ or .015" out of the plane of the head 5 or cap 4 as the case may be. This insures that when a bolt 27 or other fastener is placed in the cross bore to hold the cylinder in place against a base 28 that the head and cap of the cylinder will be tightly held against the base support. The present foot mounting also provides a shorter mounting length for a given size cylinder than was previously available. Formerly, clearance of the tie rod nuts required a longer foot mount and also one that elevated the cylinder from the base to obtain clearance for the nuts on the bolt and the normal tie rod nuts.

Referring particularly to Figure 2, it will be noted that a portion 26 of the mounting lug extends over the retain-

ing plate 6 a sufficient distance to be within the line of the cylinder tube 3. The force applied to the tie rod by tightening the mounting lug is thus directly in line with the cylinder tube. This avoids distortion and contributes to the rigidity of the mounting. Any action of the cylinder under load will be transferred to the mounting along the line of the tie rods. This line of action is substantially closer to the center line of the cylinder than has heretofore been accomplished with side or foot type of mountings. In the past, mountings on the side of a cylinder permitted a visible bending and movement of the cylinder under heavy loads. These side mountings being at the outer sides of the cylinder were farther from the center line of the cylinder and thus did not resist beam action as does the present mount. The present lugs are in part opposite the cylinder barrel and thus closer to the center line of the piston rod. Very little bending, if any, occurs when very high loads are placed on the cylinder resulting in no movement of the cylinder between adjacent mountings. Also, there is no beam action longitudinally between opposite ends of the cylinder since the milled heads are held firmly on a base support.

The present mounting is particularly advantageous in that it permits keying of the cylinder in place either at the head or cap end or simply with a bar placed against the outer end of the mounting lugs. Ordinarily, cylinders used where close tolerances are required are keyed in place to avoid any movement because of the tolerances between the fastener and the cross bore in the mounting lug. Such keying is usual practice with cylinders required for accurate work.

The mounting lugs require only one-fourth of a turn in any position to align the sides of the lug with the sides of the head or cap. In practice, it has been found that such one-fourth turn does not place a strain on the tie rod outside of the normal tolerance permitted. The mounting lug does provide a very convenient and readily adjustable means of mounting the cylinder. In operation, only the pair of nuts 8 and 9 need be removed from one tie rod at a time in order to attach the mounting. By following this procedure, the piston and cylinder assembly is not particularly disturbed. The mount has the added advantage of being interchangeable with other types of mounts as no special preparation of the cylinder or heads is required to attach the present mount. The usual tie rods are used to secure the mounting lugs to the cylinder and they may be later removed to substitute other mounts such as pivot or flange mounts.

The foregoing detailed description has been given for clearness of understanding only, and no unnecessary limitations should be understood therefrom, for some modifications will be obvious to those skilled in the art.

We claim:

1. A tie rod mounted piston and cylinder device secured against deflection due to load, comprising: a cylinder having a square head at each end and tie rods extending through the heads, a plurality of one piece lugs each hav-

ing an internally threaded nut portion at one end for tightening the lugs upon threaded ends of the tie rods against the adjacent cylinder head to hold the cylinder and heads together, each lug having a cross bore extending

5 through the lug adjacent to said nut portion for receiving a bolt fastener to hold the attached cylinder device heads against a base, said cross bore being aligned longitudinally with its respective tie rod, said lugs having sides spaced slightly inwardly of the sides of the adjacent 10 head to secure the head against the base and loads on the cylinder being transferred through the lugs to the base substantially along the line of the tie rods.

2. A foot mounted piston and cylinder device, comprising: a cylinder having heads and tie rods extending 15 through the heads, each head having a flat surface for supporting the cylinder upon a base; a plurality of tie rod mounting lugs each having a nut portion threaded upon one end of the tie rods adjacent said flat surfaces, a flat face on each lug for abutting the face of the adjacent head and a pair of parallel surfaces normal to said flat face, said lugs each having an opening extending through said parallel surfaces to receive a fastener to secure the device on the base, said openings being aligned longitudinally with the tie rods so as to position the securing 20 fasteners relatively near the center line of the cylinder avoiding beam action under heavy loads.

3. A tie rod mount as specified in claim 2 wherein the lug is square in cross-section and is of a size substantially to align at least two sides thereof with square sides of a 25 cylinder head, said sides of the lug being spaced inwardly of the sides of the cylinder head not substantially more than .015 inch.

4. A foot mounted piston and cylinder device, comprising: a cylinder having heads and tie rods extending 30 through the heads, each head having a flat surface for supporting the cylinder upon a base; a plurality of tie rod mounting lugs each having a nut portion threaded upon one end of the tie rods adjacent said flat surfaces, a flat face on each lug for abutting the face of the adjacent head 35 and a pair of spaced surfaces extending from said flat face generally in the direction of the tie rod, said lugs each having an opening extending through said spaced surfaces generally normal to the respective tie rods to receive a fastener for securing the device on the base, said openings 40 being aligned longitudinally with the tie rods so as to position the securing fasteners relatively near the center line of the cylinder avoiding beam action under heavy loads.
